UNITED STATES PATENT OFFICE.

SAMUEL S. STOLE, OF MANSFIELD, OHIO, ASSIGNOR TO THE OHIO BRASS COMPANY,
OF MANSFIELD, OHIO, A CORPORATION OF NEW JERSEY.

CIRCUIT CHANGER.

Application filed September 1, 1922. Serial No. 585,639.

To all whom it may concern:

Be it known that I, SAMUEL S. STOLE, a citizen of the United States, and resident of Mansfield, county of Richland and State of Ohio, have invented certain new and useful Improvements in Circuit Changers, of which the following is a specification, and which are illustrated in the accompanying drawings, forming a part thereof.

10 The invention relates to an improved circuit changer used in conjunction with a solenoid, the latter being employed, for example, for automatic operation of an electric railway switch. When used for this purpose, 15 and in the preferred form herein selected for illustration, the invention contemplates the provision of a contactor or pan on the trolley wire or the like in advance of the switch, a double solenoid actuating the switch, a 20 constantly closed circuit of relatively high resistance connecting the solenoid windings with the trolley wire, and a circuit changer operable to selectively direct current at high amperage into the different solenoid windings for a predetermined but definitely limited 25 interval of time, in accordance with the entrance of the trolley into the pan with power on or power off, the said operation being independent of the duration of the 30 contact of the trolley with the pan or changes in the condition of the power circuit of the car during the period of contact.

As heretofore constructed electric switch operating devices have required contact of 35 the trolley wheel with the pan for an appreciable time period in order that complete saturation of the solenoid should occur. This time period has been secured by making the parts of considerable length and by limiting the speed of the car in passing the pan. The limitation of speed of the car introduces 40 the personal equation of the motorman and to that extent such a construction is not automatic. It is, therefore, one of the objects of the invention to provide a circuit changer, which, when set in operation upon 45 contact of the trolley wheel with the pan, insures the application of current to the solenoid for a sufficient length of time to obtain its complete saturation without continuing 50 the application long enough to injure the solenoid under any circumstances. To this end the invention provides an assembly of apparatus comprising a plurality of parts, 55 operating in succession following an instantane-

ous contact of the trolley wheel with the pan, the operation of each part contributing a definite time element to the period during which the solenoid is energized. It is also to be noted that in the preferred form of the invention, as illustrated, the constant application of current at low amperage in connection with the form of solenoid employed, facilitates the movement of the switch under the application of power and serves to hold the switch against movement at other times. The improved arrangements of circuits and relays are further designed to avoid serious arcing at the contacts and interference with the desired operation by static discharges.

The accompanying drawing is a diagrammatic view of the improved circuit changer as adapted to an automatic switching device for D. C. electric railways.

The overhead trolley wire is shown at 10 and a trolley pole at 11, the heating, lighting and motive power circuits of a car being designated, 12, 13 and 14, respectively. A movable switch point 15 is preferably directly connected as by means of a link 16, to the stem 17^a of the core 17 of an adjacent double solenoid 18, the position and movement of the switch point 15 being governed by the position and movement of the said solenoid core. As shown in the diagram, switch point 15 is set to direct the approaching car onto the siding 19. It follows that if the car is to continue to travel on the main line, as 20, a change must be produced in the energization of solenoid 18 to cause core 17 to move inwardly. In accordance with the usual practice the energization of the solenoid 18 is controlled in the first instance by the contact of trolley wheel 21 of the approaching car with a trolley contactor or pan 22 placed at a convenient distance in front of the switch, the condition of the power circuit, as 14 of the car determining which of the two windings, as 48, 49, of the solenoid 18 is energized.

In case it is desired to prevent a following car from causing a second operation of the switch before the first car has traveled a certain distance beyond, a second pan 23 may be provided. As the trolley 10 is divided at the switch, it is understood that a pan 23 will be mounted upon each branch of the trolley beyond the switch, but for simplicity of illustration the branching of the

trolley wire is omitted from the diagram and only one pan 23 is shown. In the event it is desired to omit pan 23, the switch indicated at 24 should be opened. This is the only change required in event pan 23 is not used.

Pan 22 preferably includes a pair of side bars 27 and 28. These side bars are insulated from each other and one of them, as 19 28, is normally insulated from trolley wire 10. The other side bar, as 27, is connected with the trolley wire 10 at all times, as through conductors 29, 30, main winding 31 of a circuit changing relay A and conductor 15 32. As is common in the construction of trolley contactors of the type in question, side bars 27 and 28 are so positioned that trolley wheel 21 in passing under the pan is disengaged from trolley wire 10 and forms 20 both a conductor between side bars 27 and 28 and a path for current from side bar 27 to ground. This path for current to ground is through trolley pole 11 and the various circuits, as 12, 13, 14 of the car, the 25 amount of current drawn through the main winding 31 of the circuit changing relay A, when trolley wheel 21 contacts with the pan, being principally determined by the condition of the power circuit 14 of the car.

30 The bridging of side bars 27 and 28 of the pan by trolley wheel 21 completes a circuit connecting winding 33 of relay B with trolley wire 10. Relay B is accordingly energized regardless of whether power is on or off. The circuit through relay B includes wires 29 and 30, main winding 31 of relay A, wire 32, side bar 27, trolley wheel 21, side bar 28, and wires 35 and 36. Winding 33 of relay B is of relatively high resistance, 35 preferably approximately 500 ohms when a 600 volt circuit is used. Winding 33 is grounded through wire 38, a relatively high limiting resistance 39 and wire 40.

An important feature of the invention is 45 the provision of two front contacts 41 and 42 for the armature 43 of relay B. In its lifted position, armature 43 is directly connected with trolley wire 10, through wire 29, wire 44, fuse 45, wire 46 and front contact 42. So long as trolley wheel 21 remains in contact with the pan 22 armature 43 also has a connection with trolley wire 10 through front contact 41, this connection comprising wires 29, 30, winding 31, wire 50 32, the two side bars 27, 28 of the pan and wires 35, 36 and 37.

The armature 34 of circuit changing relay A is directly connected with armature 43 of relay B, as through wire 47. Armature 34 60 is accordingly connected with trolley wire 10 when armature 43 is in its lifted position. It follows that armature 34 is always connected with trolley wire 10 upon the entrance of trolley wheel 21 into the pan. If 65 power is off, armature 34 remains in its low-

ered position. Under these circumstances winding 49 of solenoid 18 is energized, the path for current being from trolley wire 10 through armature 34, back contact 50, and wires 51 and 56.

Wheel 21 in pan 22, with power on, connects armature 34 with trolley wire 10 in the same manner as with power off, but causes sufficient energization of relay A to lift armature 34. Current is accordingly 75 directed into solenoid winding 48 through front contact 53, the path for current being now through a second winding 54 on relay A and wires 55 and 52. The purpose of winding 54 on relay A is to hold armature 80 34 in its lifted position in event trolley wheel 21 leaves the pan 22 before the time provided for saturation of solenoid winding 49, as determined by other parts of the apparatus, has elapsed. Since energization 85 of winding 48 moves switch point 15 to the position shown in the diagram and energization of winding 49 throws the switch to open the main line, it follows that the car should coast into the pan if it is to continue on the main line and should enter the pan with power on if it is to take the siding.

Another important feature of the invention is the provision of a relay C, having a winding 57, which is normally energized. 95 As shown, relay 57 has two windings 57 and 71, its main winding 57 being connected with trolley wire 10 through wires 29 and 58. In the particular arrangement illustrated the current normally supplied to the 100 main winding 57 of relay C is divided and supplied in equal amounts to the two windings 48 and 49 of solenoid 18. The current thus constantly supplied to windings 48 and 49 is of low amperage, but raises the temperature of the solenoid sufficiently to prevent snow and ice from accumulating on the solenoid casing and serves to keep the windings dry. When the solenoid core 17 is relatively short, as shown, the continuous 110 flow of current into the solenoid windings also creates a corresponding flux differential in the two ends of the solenoid in accordance with the position of the core. This flux differential has a buoyant effect on core 17 115 permitting it to move easily. This flux differential also serves to lock the switch electrically in either position rendering the use of knuckles, springs or other mechanical holding devices unnecessary. It further 120 acts as a dynamic brake to prevent too rapid movement and a possible rebound of the switch point 15. It will be understood that the locking of the switch in its different 125 positions arises from the fact that while there is a continuous flow of current in both of the windings 48 and 49 of the solenoid, the winding at the end of the solenoid in which the core is located is most effective upon it.

Since winding 57 is normally energized by its connection with trolley wire 10, armature 63 is normally held in elevated position, as shown. When trolley wheel 21 enters pan 22, the main winding 57 of relay C is shunted out through wires 35 and 59, its armature 63, falling by gravity, preferably upon two back contacts 64 and 65. When switch 24 is closed the shunting out of the main winding 57 of relay C is continued by the closing of back contact 64 regardless of whether current is supplied to wire 35 from the pan 22 or not, wire 35 being now directly connected to trolley wire 10 through armature 63, back contact 64, wire 78, switch 24 and wire 29. It follows that armature 63 of relay C remains down until it is lifted by engagement of the trolley wheel 21 with pan 23 in the manner herein-
after explained.

In the arrangement shown, the release of armature 63 of relay C is retarded in two ways, each contributing a separate time factor in the energization of the track solenoid. One method of retarding the release of armature 63 consists in shunting out winding 57, as described, as distinguished from opening the circuit through this relay. In addition, winding 57 is preferably also formed with a copper sleeve 67 on its core 66 to retard the release of the armature in a well known manner. Furthermore, back contacts 64 and 65 may be so located as to require armature 63 to fall through an appreciable distance before engaging these contacts, thus contributing a third time factor in the energization of the track solenoid.

When armature 63 drops onto back contact 65, winding 33 is shunted out by current through wires 68 and 35. The shunting out of relay 33 furnishes a fourth time factor and the retarded release of armature 43 due to a copper sleeve 69 mounted on core 70 furnishes the fifth and final time factor in the energization of the solenoid windings. Armature 43 in dropping breaks the circuit through armature 34 to the solenoid 18. There is accordingly no further application of current to either of the windings 48 and 49 of solenoid 18, except the small amount constantly furnished through resistances 60 and 61, regardless of whether trolley wheel 21 has left the pan 22 or not. Furthermore, there can be no further application of current to either of the windings of solenoid 18 until armature 63 of relay C has been lifted and when switch 24 is closed this does not occur until trolley wheel 21 engages pan 23. Winding 71 of relay C is then energized by current from trolley wire 10 through wire 72, side bar 73, trolley wheel 21, side bar 74 and wire 75, winding 71 of relay C being grounded through wire 76. To avoid injury to winding 71 of relay

C in event a car should stand for any length of time with its trolley wheel 21 in engagement with pan 23, this winding is preferably made of high resistance, as much as 12,000 ohms being desirably used in a 600 volt circuit.

Should the second pan 23 be omitted, wire 75, the second winding 71 on relay C, and the back contact 64 of this relay become unnecessary and switch 24 should be opened. Armature 63 of relay C is then lifted as soon as the trolley wheel 21 leaves the pan 22, except that if the movement of the trolley wheel through the pan occupies less time than the pick up and release of armature 43, armature 63 of relay C will not be lifted until after the release of armature 43 has occurred, the shunting out of winding 57 being continued while armature 43 of relay B is lifted by a shunt path for current including wires 51 and 56 or 55 and 52 depending upon the position of armature 34 of relay A.

The operation of the device in the form shown is as follows. A small amount of current is constantly supplied to each of the windings 48 and 49 of the track solenoid 18. This solenoid is accordingly kept warm and dry at all times and the movable switch point 15 is held locked in the position to which it was last moved by the greater effect upon the solenoid core 17 of the winding, as 48, at the end of the solenoid in which the core is located at the time.

In approaching the switch the trolley wheel 21 of the car engages the pan 22. Current is thus drawn through the main windings of the circuit changing relay A through the heating, lighting and power circuits 12, 13, 14 of the car, the amount of current required for the heating and lighting circuits 12, 13, being insufficient to lift armature 34. It follows that if the car is coasting armature 34 will remain in its lowered position while if the car is proceeding under power armature 34 will be lifted to close front contact 53.

Engagement of the trolley wheel 21 with the pan 22 serves also to lift armature 43 of relay B and release armature 63 of relay C. When armature 43 is lifted, power is supplied direct from the trolley wire 10 to one or the other of the windings 48, 49, of the track solenoid 18, depending upon the position of armature 34 of relay A. However, engagement of the armature 63 with its back contact 65 serves to shunt out relay B. Interruption of the supply of current to the appropriate winding 48, 49, of the track solenoid 18 accordingly follows automatically, the length of time during which solenoid 18 is energized being equal to the sum of five time intervals as follows. First, the time required for shunting out relay 57; second, the time required for release of ar-

mature 63 owing to the provision of a copper sleeve 67 on the core 66 of relay C; third, the time required for armature 63 to reach its back contact 65; fourth, the time required for shunting out winding 33, and fifth, the time required for release of armature 43 owing to the provision of a copper sleeve 69 on the core 70 of relay B.

So long as armature 63 remains upon its back contact 65 winding 33 is shunted out and there can be no second operation of the switch. When a second pan 23 is used and switch 24 is closed, winding 57 is shunted out from the time the trolley wheel 21 engages pan 22 until it reaches pan 23. In case no second pan, as 23, is provided and switch 24 is opened, or this switch and its connections omitted, winding 57 is shunted out and there can be no second operation of the switch while the trolley wheel 21 is engaged with pan 22, and until armature 43 of relay B is released.

The feature of supplying power to the track solenoid 18 directly from the trolley wire 10, as distinguished from the pan 22 where it would be added to the amount drawn through winding 31 by the heating, lighting and power circuits 12, 13, 14, of the car, is not claimed broadly herein for the reason that such broad claims are made in my pending application for patent on circuit changers, Serial No. 493,258 filed August 18, 1921.

It will be understood that the current constantly supplied to relay C through wires 29 and 58 is divided between the two windings 48 and 49 of the track solenoid 18 by passing through wire 62 and thence through separate paths comprising resistance 61 and wire 52, and resistance 60 and wire 56, respectively. Furthermore, windings 48 and 49 of track solenoid 18 both have a connection to ground through wire 77. Since a small amount of current is passing through coils 60 and 61 at all times, these coils may also be used as heater coils, and if they are enclosed within the same case with track solenoid 18 they will assist in keeping the interior of the case warm and dry.

The resistance of winding 57 is such that the normal flow of current through it will not be sufficient to permit energizing the winding 33 of relay B when the system is in normal condition, that is, when relays A, B and C are in the condition shown in the drawing.

I claim as my invention:

1. In combination, a double wound solenoid, a main circuit including a circuit changer connecting the solenoid to a source of power for selective temporary energization of the different windings of the solenoid in accordance with predetermined conditions and a second circuit of relatively high resistance constantly connecting both

windings of the solenoid with the same source of power.

2. In combination, a double wound solenoid, a main circuit including a circuit changer connecting the solenoid to a source of power for selective temporary energization of the different windings of the solenoid in accordance with predetermined conditions and a second circuit of relatively high resistance connecting both windings of the solenoid with the same source of power at all other times.

3. In an electric switch operating device, in combination, a double wound solenoid and its core, one of said parts being movable, a movable switch element, operative connection between the movable switch element and the movable one of the two first mentioned parts, a main circuit including a circuit changer connecting the solenoid to a source of power for selective temporary energization of the different windings of the solenoid upon the approach of a car with power on or power off, and a second circuit of relatively high resistance constantly connecting both windings of the solenoid with the same source of power.

4. In an electric switch operating device, in combination, a double wound solenoid and its core, one of said parts being movable, a movable switch element, operative connection between the movable switch element and the movable one of the two first mentioned parts, a main circuit including a circuit changer connecting the solenoid to a source of power for selective temporary energization of the different windings of the solenoid upon the approach of a car with power on or power off, and a second circuit of relatively high resistance connecting both windings of the solenoid with the same source of power at all other times.

5. In combination, a double wound solenoid and its core, the said two parts being relatively movable between two different positions and the solenoid and core being constructed for different effects of the two windings of the solenoid upon the core in the said two positions, a main circuit including a circuit changer connecting the solenoid to a source of power for selective temporary energization of the different windings of the solenoid in accordance with predetermined conditions, and a second circuit of relatively high resistance constantly connecting both windings of the solenoid with the same source of power.

6. In combination, a double wound solenoid and its core, the said two parts being relatively movable between two different positions and the solenoid and core being constructed for different effects of the two windings of the solenoid upon the core in the said two positions, a main circuit including a circuit changer connecting the solenoid

to a source of power for selective temporary energization of the different windings of the solenoid in accordance with predetermined conditions, and a second circuit of relatively high resistance connecting both windings of the solenoid with the same source of power at all other times.

7. In an electric switch operating device, in combination, a double wound solenoid and its core, the said two parts being relatively movable between two different positions and the solenoid and core being constructed for different effects of the two windings of the solenoid upon the core in the said two positions, a movable switch element, operative connection between the movable switch element and the movable one of the two first mentioned parts, a main circuit including a circuit changer connecting the solenoid to a source of power for selective temporary energization of the different windings of the solenoid upon the approach of a car with power on or power off and a second circuit constantly connecting both windings of the solenoid with the same source of power.

8. In an electric switch operating device, in combination, a double wound solenoid and its core, the said two parts being relatively movable between two different positions and the solenoid and core being constructed for different effects of the two windings of the solenoid upon the core in the said two positions, a movable switch element, operative connection between the movable switch element and the movable one of the two first mentioned parts, a main circuit including a circuit changer connecting the solenoid to a source of power for selective temporary energization of the different windings of the solenoid upon the approach of a car with power on or power off, and a second circuit connecting both windings of the solenoid with the same source of power at all other times.

9. In combination, a double wound solenoid, a main circuit including a circuit changer connecting the solenoid to a source of power for selective temporary powerful energization of the different windings of the solenoid in accordance with predetermined conditions and a second circuit of relatively high resistance connecting the solenoid with the same source of power for continued feeble energization of one of its windings after powerful energization of the same winding through the said main circuit.

10. In an electric switch operating device, in combination, a double wound solenoid and its core, one of said parts being movable, a movable switch element, operative connection between the movable switch element and the movable one of the two first mentioned parts, a main circuit including a circuit changer connecting the solenoid

to a source of power for selective temporary powerful energization of the different windings of the solenoid upon the approach of a car with power on or power off and a second circuit of relatively high resistance connecting the solenoid with the same source of power for continued feeble energization of one of its windings after powerful energization of the same winding through the said main circuit whereby the said movable switch element is electro-magnetically locked in position after movement in one direction.

11. In combination, a double wound solenoid, a main circuit including a circuit changer connecting the solenoid to a source of power for selective temporary powerful energization of the different windings of the solenoid in accordance with predetermined conditions and a second circuit of relatively high resistance connecting the solenoid with the same source of power for continued feeble energization of each of its windings immediately following powerful energization of the same winding through the said main circuit.

12. In an electric switch operating device, in combination, a double wound solenoid and its core, one of said parts being movable, a movable switch element, operative connection between the movable switch element and the movable one of the two first mentioned parts, a main circuit including a circuit changer connecting the solenoid to a source of power for selective temporary powerful energization of the different windings of the solenoid upon the approach of a car with power on or power off and a second circuit of relatively high resistance connecting the solenoid with the same source of power for continued feeble energization of each of its windings immediately following powerful energization of the same winding through the said main circuit whereby the said movable switch element is electro-magnetically locked in position after each operation thereof.

13. In combination, a plural wound solenoid and its core, the said two parts being relatively movable between different positions and the solenoid and core being constructed for effects of the several windings of the solenoid upon the core differing in magnitude for the same current in the different positions of the parts, means constantly furnishing equal holding currents in all of the solenoid windings and means selectively furnishing a temporary operating current in the different solenoid windings.

14. In combination, a plural wound solenoid, means selectively supplying a temporary operating current in the different windings of the solenoid and means furnishing a continued holding current in one of the solenoid windings immediately following the

- temporary supply of an operating current to the same winding.
15. In combination, a plural wound solenoid, means selectively supplying a temporary operating current in the different windings of the solenoid and means furnishing a continued holding current in each of the solenoid windings immediately following the temporary supply of an operating current to the same winding.
16. In an electric switch operating device, in combination, a plural wound solenoid and its core, the said two parts being relatively movable between different positions and the solenoid and core being constructed for effects of the several windings of the solenoid upon the core differing in magnitude for the same current in the different positions of the parts, a movable railway switch element, operative connection between the said switch element and the movable one of the two first mentioned parts, means constantly furnishing equal holding currents in all of the solenoid windings and means selectively furnishing a temporary operating current in the different solenoid windings.
17. In an electric switch operating device, in combination, a plural wound solenoid and its core, one of said parts being movable, a movable railway switch element operatively connected to the movable one of the two first mentioned parts, means selectively supplying a temporary operating current in the different windings of the solenoid and means furnishing a continued holding current in one of the solenoid windings immediately following the temporary supply of an operating current to the same winding whereby the said switch element is electro-magnetically locked after movement to one of its positions.
18. In an electric switch operating device, in combination, a plural wound solenoid and its core, one of said parts being movable, a movable railway switch element operatively connected to the movable one of the two first mentioned parts, means selectively supplying a temporary operating current in the different windings of the solenoid and means furnishing a continued holding current in each of the solenoid windings immediately following the temporary supply of an operating current to the same winding whereby the said switch element is electro-magnetically held against movement after each operation thereof.
19. In an electric switch operating device, the combination of a movable switch element, electro-magnetic means for moving the switch element, a power line, a current collector, a contactor for cooperation with the current collector to cause the operation of said means, and electro-magnetic means for holding the switch element against movement after operation thereof.

20. In an electric switch operating device, the combination of a movable switch element, means for moving the switch element including a solenoid, a power line, a contactor, a current collector for cooperating with the contactor to supply a temporary operating current to the solenoid and means for supplying a holding current to the solenoid.
21. In an electric switch operating device, the combination of a relatively movable solenoid and its core, a switch element operatively connected to the movable one of the first mentioned parts, a low resistance circuit including the solenoid, a power line, a contactor, a current collector for cooperating with the contactor to temporarily close the low resistance circuit with the power line, and a high resistance circuit connecting the solenoid with the power line.
22. In combination, a double wound solenoid, means selectively supplying an operating current to the different windings of the solenoid and means constantly supplying current at relatively low amperage to both of the solenoid windings.
23. In an electric switch operating device, the combination of a relatively movable double wound solenoid and its core, a movable switch element operatively connected to the movable one of the two first-mentioned parts, selective means for directing current through the different windings of the solenoid, a power line, a contactor, a current collector for cooperating with the contactor to supply operating current to the solenoid, and means for supplying current at relatively low amperage to both solenoid windings.
24. In an electric switch operating device, the combination of a power line, a contactor, a track solenoid, a normally open circuit of low resistance connecting the power line with the track solenoid, a current collector adapted to cooperate with the contactor to temporarily close said circuit, a second high resistance circuit connecting the track solenoid with the source of power and a heater coil associated with the track solenoid in the last named circuit.
25. In an electric switch operating device, the combination of a power line, a track solenoid, a normally open circuit connecting the power line with the solenoid, a contactor, a current collector adapted to cooperate with the contactor to close said circuit and temporarily furnish an operating current to the track solenoid, and a second circuit constantly furnishing a heating current to the solenoid.
26. In an electric switch operating device, the combination with the track solenoid and a source of power of connections between the said two parts temporarily furnishing an operating current to the track solenoid and constantly furnishing a heating current thereto, and a contactor and a current col-

lector adapted to cooperate therewith to make effective the connection for furnishing the operating current.

27. In an electric switch operating device, 5 the combination with the track solenoid, trolley wire and trolley contactor, of a normally open low resistance circuit and a normally closed high resistance circuit both connecting the track solenoid with the trolley 10 wire and means controlled by contact of a trolley with the trolley contactor for closing the said low resistance circuit.

28. In an electric switch operating device, 15 the combination with the track solenoid, trolley conductor and trolley contactor, of a normally open circuit connecting the trolley conductor and track solenoid, of means controlled by contact of a trolley with the trolley contactor for closing the said circuit, a 20 normally energized relay permitting operation of the said circuit closing means when energized but preventing operation of the circuit closing means when released and means for releasing the relay controlled by 25 the said trolley contact.

29. In an electric switch operating device, the combination with the track solenoid, trolley conductor and trolley contactor, of a normally open circuit connecting the trolley 30 conductor and track solenoid, of means controlled by contact of a trolley with the trolley contactor for closing the said circuit, a normally energized retarded release relay permitting operation of the said circuit closing 35 means when energized but preventing operation of the circuit closing means when released and means for releasing the relay controlled by the said trolley contact.

30. In an electric switch operating device, 40 the combination with the track solenoid, trolley conductor and trolley contactor, of a normally open circuit connecting the trolley conductor and track solenoid, of means controlled by contact of a trolley with 45 the trolley contactor for closing the said circuit, a normally energized relay permitting operation of the said circuit closing means when energized but preventing operation of the circuit closing means when released, a 50 shunt for the relay closed by the said trolley contact, and a back contact for the relay continuing the relay shunt independent of the trolley contactor.

31. In an electric switch operating device, 55 the combination with the track solenoid, trolley conductor and trolley contactor, of a normally open circuit connecting the trolley conductor and track solenoid, of means controlled by contact of a trolley with 60 the trolley contactor for closing the said circuit, a normally energized relay permitting operation of the said circuit closing means when energized but preventing operation of the circuit closing means when released, a

shunt for the relay closed by the said trolley 65 contact, a back contact for the relay continuing the relay shunt independent of the trolley contactor and a manual switch controlling the said back contact.

32. In an electric switch operating device, 70 the combination with the track solenoid, trolley conductor and trolley contactor, of a normally open circuit connecting the trolley conductor and track solenoid, of a relay in circuit with the trolley contactor 75 for closing the said normally open circuit, a relay in circuit with the trolley conductor preventing pick up of the first mentioned relay when released, and a shunt for the second mentioned relay in circuit with the trolley contactor.

33. In an electric switch operating device, the combination with the track solenoid, trolley conductor and trolley contactor, of a normally open circuit connecting the trolley 80 conductor and track solenoid, of a relay in circuit with the trolley contactor for closing the said normally open circuit, a relay in circuit with the trolley conductor preventing pick up of the first mentioned relay 90 when released, and a shunt for the second mentioned relay controlled by the first mentioned relay.

34. In an electric switch operating device, 95 the combination with the track solenoid, trolley conductor and trolley contactor, of a normally open circuit connecting the trolley conductor and track solenoid, of a relay in circuit with the trolley contactor for closing the said normally open circuit, a relay in 100 circuit with the trolley conductor preventing pick up of the first mentioned relay when released, and two shunts for the second mentioned relay, one being in circuit 105 with the trolley contactor and the other being in circuit with the trolley conductor independent of the trolley contactor but controlled by the first mentioned relay.

35. In an electric switch operating device, 110 the combination with the track solenoid, trolley conductor and trolley contactor, of a normally open circuit connecting the trolley conductor and track solenoid independent of the trolley contactor, a relay normally in circuit with the trolley contactor and having two front contacts, one controlling the said normally open circuit and the other connecting the relay with the trolley conductor independent of the trolley contactor, 115 a relay in closed circuit with the trolley conductor at all times, a shunt for the last mentioned relay in circuit with the trolley contactor, and a back contact for the second mentioned relay controlling a shunt for the first mentioned relay.

36. In an electric switch operating device, 120 the combination with the track solenoid, trolley conductor and trolley contactor, of a

normally open circuit connecting the trolley conductor and track solenoid independent of the trolley contactor, a retarded release relay normally in circuit with the trolley contactor and having two front contacts, one controlling the said normally open circuit and the other connecting the said relay with the trolley conductor independent of the trolley contactor, a second retarded release relay in closed circuit with the trolley conductor at all times, a back contact for the second mentioned relay controlling a shunt for the first mentioned relay and a shunt for the second mentioned relay in circuit with the trolley contactor.

37. In a switch operating system, the combination of an electrically operated track switch, an operating circuit therefor, a circuit changer for said track switch, a normally open switch to control the circuit and

to shunt out the circuit changer and electrically operated means provided with a single operating coil to shunt out the normally open switch after it has been closed and maintain said means closed while current is on the system.

38. In a switch operating system, the combination of an electrically operated track switch, a branched operating circuit, a circuit changer for the operating circuit provided with a positioning coil, a holding coil in one of the branches, a normally open switch to control the operating circuit and electrically operated means provided with a single operating coil to close the said means and to maintain it closed to shunt out the normally open switch to open the switch and maintain it open after the track switch has been operated.

SAMUEL S. STOLP.
